UNITED STATES PATENT OFFICE.

THOMAS A. WATTS, OF SPRINGFIELD, OHIO, ASSIGNOR TO THE SPRINGFIELD METALLIC CASKET COMPANY, OF SPRINGFIELD, OHIO, A CORPORATION OF OHIO.

LATCH.

1,422,504.

Specification of Letters Patent. Patented July 11, 1922.

Application filed January 10, 1921. Serial No. 436,265.

To all whom it may concern:

Be it known that I, THOMAS A. WATTS, a citizen of the United States, residing at Springfield, in the county of Clark and State of Ohio, have invented certain new and useful Improvements in Latches, of which the following is a specification.

My invention relates to improvements in catches, and it more particularly relates to catches for fastening the lids of burial caskets.

The object of my invention is to provide a catch which is of simple construction and effective in operation, and also one the parts of which may be easily and quickly assembled without the employment of rivets or other similar securing devices.

In the accompanying drawings:

Fig. 1 is a front elevation of a latch embodying my improvements.

Fig. 2 is a side elevation of the same.

Fig. 3 is a rear elevation of the same.

Fig. 4 is a top plan view.

Fig. 5 is a vertical section on the line 5—5 of Fig. 1.

Referring to the drawings, 1 represents a plate having a rectangular-shaped opening 1^a, positioned midway the width of the plate, lying for the greater part below the center thereof. The plate also has a rectangular-shaped notch 1^b, in its upper edge in vertical alinement with the opening 1^a, and is further provided at either side with a round opening 1^c to receive the screws or other fastening devices which secure it to the casket cover.

Attached to the rear side of the plate 1, is a housing, the rear wall of which is represented by 2, the side walls by 2^a and the bottom by 2^b; the front of the housing being closed by the plate and the top being open. The rear wall, it will be noticed, is inclined so that the housing is of less depth at the bottom than at the top. In order to secure the housing to the plate, I form on the upper forward corner of each of the sides thereof, and also on the forward edge of the bottom thereof, lips 2^c, the upper ones being projected through the notch 1^b, and the lower ones under the plate 1 and then bent or clinched against the forward face of the plate to firmly clamp the housing to the plate.

A latch 3 is supported by the plate and housing thus formed. The central portion

3 thereof lies within the housing back of the plate, with the lower end 3^a bent at right-angles in a forward direction and projecting through the opening 1^a to form the latch proper, and the upper portion bent at substantially right-angles and projected through the notch 1^b, as indicated at 3^b; the extreme outer end of the upper portion being bent upwardly as indicated at 3^c to form a finger piece. The outer edge of the turned-over part of the portion 3^a engages with the keeper (not shown). Extending laterally from each side of the latch at the juncture of the portions 3 and 3^a is a trunnion 5; these trunnions being journaled in the walls of openings 5^a formed in the sides of the housing.

Located in the housing is a curved flat spring 4, the extreme upper end thereof bearing against the latch portion 3^b, at a point but slightly removed from the juncture of the portions 3 and 3^b, and the central back portion thereof against the rear wall 2 of the housing; the extreme lower end thereof being bent upwardly as indicated at 4^a and bears against the rear side of the plate 1 just beneath the latch; the contact of the upper end of the spring with the latch portion 3^b and the inclination of the back wall of the housing serving to hold the spring against downward movement, and contact of the part 4^a with the latch preventing upward movement.

The tendency of the spring is to throw the latch member to latching position, or to the position shown in the drawings.

By the construction described, it will be seen that a very simple latch is provided of few parts which may be readily assembled and held in assembled position without the aid of rivets or other securing devices.

Having thus described my invention, I claim:

1. In a device of the character described, a plate, a housing secured thereto, a latch partly located in said housing, and a flat spring in said housing bearing on said latch and also having a bearing point on one wall of the housing and also on said plate to provide for supporting the same.

2. In a device of the character described, a plate, a housing secured thereto, a latch partly located in said housing, and a flat spring in said housing bearing on said

latch, the rear wall of said housing being inclined so that the said housing decreases in depth toward the lower end, said spring having a bearing point against the rear wall of said housing and also against said front plate.

3. In a device of the character described, a plate, a housing secured thereto, the rear wall of said housing being inclined so that 10 said housing decreases in depth toward the bottom, a latch partly located in said housing with its lower end bent and projected through an opening in said plate, and a flat spring in said housing having its upper 15 end bearing on said latch and its lower end bent upwardly and bearing on said plate beneath the lower end of said latch, with

its central portion bearing on the rear wall of said housing.

4. In a device of the character described, 20 a supporting plate, a housing secured thereto, a latch pivotally supported by the side walls of the housing, the lower end of said latch being extended through an opening in said plate and the upper end extended to 25 a point beyond the front face of said plate, and a flat spring in said housing having bearing points, respectively, on the latch, rear wall of the housing and plate.

In testimony whereof, I have hereunto 30 set my hand this 4th day of January 1921.

THOMAS A. WATTS.

Witness:

CHAS. I. WELCH.
